GRINDING MACHINE

Merle S. Bendickson, San Gabriel, Calif.

Application April 22, 1952, Serial No. 283,717

11 Claims. (Cl. 51—67)

1
This invention relates to apparatus for grinding tapered joints, stop cocks, or other work pieces.

An object of my invention is to provide a machine for grinding work pieces to a predetermined shape by moving grinding elements axially along the surface of a rotating work piece as it is rotated.

Another object of my invention is to provide a machine in which grinding elements are reciprocated under pressure along a surface of a rotating work piece to be ground.

Another object of my invention is to provide such machine with means for relieving the force urging the grinding elements against the work piece when the work piece has been ground to a predetermined shape.

Still another object of my invention is to provide adjustable stops for establishing the ultimate line of movement of a reciprocating arm carrying a grinding element so as to vary the size and shape of a finished article formed by grinding a work piece against which the grinding element is pressed.

The foregoing and other objects of my invention together with various advantages thereof may be ascertained from the following description taken in connection with the accompanying drawings wherein:

Fig. 1 is a horizontal sectional view of a grinding machine incorporating features of my invention;

Fig. 2 is a longitudinal vertical sectional view taken on the plane 2—2 of Fig. 1;

Fig. 3 is an enlarged fragmentary vertical sectional view taken on the plane 3—3 of Fig. 1;

Fig. 4 is a sectional transverse view taken on the plane 4—4 of Fig. 3;

Fig. 5 is a transverse vertical sectional view taken on the plane 5—5 of Fig. 3;

Figs. 6, 7 and 8 are diagrams showing relative positions of various working parts of the grinding machine at various points in its operation;

Fig. 9 is a cross-sectional view taken on the plane 9—9 of Fig. 3; and

Fig. 10 is a fragmentary longitudinal sectional view of an alternative form of centering element.

Referring to the drawing, and more particularly to Figs. 1 and 2 thereof, there is illustrated a grinding machine incorporating various features of my invention. My grinding machine includes a pair of grinding elements in the form of abrasive blocks, 10a and 10b mounted at the front ends of two corresponding working arms 12a and 12b that are reciprocated along lines that are inclined to a grinding axis X—X. Resilient

means such as a rubber band 14 encircling the two straight working arms 12a and 12b urge these working arms inwardly, pressing the inner ends of the grinding elements 10a and 10b against the outer surface of a work piece in the general shape of a stop cock 16. According to my invention the two working arms 12a and 12b are reciprocated together back and forth along their lengths as the work piece 16 is rotated and suitable means are provided for limiting the inward movement of the working arms to a predetermined ultimate grinding position in which the pressure exerted by the grinding elements 12a and 12b against the work piece 16 is relieved, thus establishing the final finished shape of the stop cock so ground.

In the specific embodiment of my invention here illustrated, a bed plate 18 and a cover 20 supported thereon constitute a housing for many of the working parts of the machine. In normal use, the bed plate 18 is laid flat upon a table 24 or other supporting surface. The cover 20 is provided with a flexible wall 22 at the front end thereof through which the working arms 12a and 12b project, thereby supporting the grinding elements 10a and 10b externally and many of the working parts of the machine internally, all as more specifically described hereinbelow.

It will be noted that the flexible wall 22 separates the grinding elements 10a and 10b from the various other working parts enclosed within the housing. This arrangement facilitates reciprocation of the working arms 12a and 12b during grinding and at the same time minimizes leakage of grinding fluid into the housing.

Two main base plates 26a and 26b dove-tailed to the bed plate 18 are independently laterally movable thereon. Two auxiliary base plates 28a and 28b dove-tailed to the respective main base plates 26a and 26b respectively, are independently movable laterally with respect to the corresponding main base plates.

The lateral movement of the two main base plates 26a and 26b is accomplished by means of a pair of coaxial oppositely threaded screws 30a and 30b, an intervening adjusting nut 32, and gearing 35 that is manipulated by means of a turning wheel 38 mounted upon the end of a shaft 40 extending through the cover 20. Inasmuch as the two screws 30a and 30b are oppositely threaded, the two main base plates 26a and 26b are moved by equal amounts in opposite directions relative to the grinding axis X—X when the wheel 38 is turned.

The movement of each of the auxiliary base plates 28a and 28b relative to its corresponding main base plate 26a or 26b is accomplished by

means of corresponding racks 42a and 42b and corresponding engaging worms 44a and 44b. The two racks 42a and 42b are secured respectively to the corresponding auxiliary base plates 28a and 28b and the two worms 44a and 44b are rotatably mounted upon the two corresponding main base plates 26a and 26b. The two racks 42a and 42b are mounted along a common line and the two worms 44a and 44b are coaxial, the two worms being independently rotatable by means of corresponding turning knobs 46a and 46b mounted at the outer ends of shafts 48a and 48b that extend through the housing.

To opposed rear guides 50a and 50b are mounted respectively at the rear ends of the two main base plates 26a and 26b. The left rear guide 50a comprises two vertically spaced rollers 52a and 53a mounted upon a bracket 54a fixed to the left main base plate 26a. The left rear guide 50a also comprises an inner vertical roller 56a mounted upon an elbow bracket 58a supported partly upon the left main base plate 26a and partly upon the bracket 54a. Likewise, the right rear guide 50b comprises two vertically spaced rollers 52b and 53b mounted upon a bracket 54a fixed to the right main base plate 26b. The left rear guide 50b also comprises an inner vertical roller 56b mounted upon an elbow bracket 58b supported partly upon the right main base plate 26b and partly upon the bracket 54b.

In a similar manner two opposed front guides 60a and 60b are mounted respectively upon the two auxiliary base plates 28a and 28b. The left front guide 60a comprises two vertically spaced rollers 62a and 63a mounted upon a bracket 64a fixed to the left auxiliary base plate 28a. The left front guide 60a also comprises an inner vertical roller 66a mounted upon an elbow shaped bracket 68a supported partly upon the left auxiliary base plate 28a and partly upon the bracket 54a and likewise, the right front guide 60b comprises two vertically spaced rollers 62b and 63b mounted upon a bracket 64b fixed to the left auxiliary base plate 28a. The right front guide also comprises an inner vertical roller 66b mounted upon an elbow bracket 68b supported partly upon the right auxiliary base plate 28b and the bracket 64b.

The left working arm 12a is mounted on the two left guides 50a and 60a passing above the two left lower rollers 53a and 63a and below the two upper rollers 52a and 62a and also externally, that is, to the left of the two vertical rollers 56a and 66a. Likewise the right working arm 12b is mounted in the two right guides 50b and 60b passing above the two right lower rollers 53b and 63b and below the two upper rollers 52b and 62b and also externally, that is to the right of the two vertical rollers 56b and 66b. The spacing between the horizontal rollers of each guide is just sufficient to permit smooth horizontal movement of the two working arms therebetween.

At the rear end of each of the two working arms 12a and 12b there are arranged slotted links 70a and 70b. Within the slot of each of the terminals, there is arranged a corresponding pair of rollers 72a and 72b, the rollers of each pair being spaced longitudinally apart on the corresponding working bar, thereby forming a gap therebetween. A reciprocating arm 74 mounted at the rear of the main base plate 18 is provided with two cross arms 76a and 76b which extend through the gaps formed by the corresponding pairs of rollers 72a and 72b. With this arrangement, the reciprocation of the bar 74 forwardly

and rearwardly causes the two working arms 12a and 12b to be reciprocated in unison along their lengths.

The reciprocation of the bar 74 is accomplished by means of a reversible electric motor 78 that drives a pinion 80 engaging a rack 82 formed at the rear end of the reciprocating bar 74. Two microswitches 84 and 86 mounted beside the reciprocating bar 74 are provided with opposed switch elements 85 and 87 which are adapted to be engaged by a finger 88 extending from the side of the reciprocating arm. Thus, as the reciprocating arm 74 is driven forward by the reversing motor, the finger 88 engages the working element 87 stopping the motor 78 and reversing its direction of rotation. Thereafter, during the rearward movement of the reciprocating arm 74 the finger 88 eventually engages the working element 85 again stopping the motor 78 and causing it to resume its forward movement. The circuit arrangement required to accomplish the repeated reversal of the direction of rotation of the reversible motor 78 may be of any conventional type.

With this arrangement, assuming that no work piece 16 is in a position to be worked upon by the grinding elements 10a and 10b the two working arms 12a and 12b are urged into contact with the two corresponding pairs of vertical rollers 56a, 66a and 56b and 66b thus establishing lines of movement along which the two working arms are constrained to move as the reciprocating arm 74 operates.

As shown in detail in Fig. 9, the two grinding elements 10a and 10b project inwardly through gaps 90a and 90b formed between pairs of fingers 92a and 92b at the front ends of the respective working arms. Bolts 94a and 94b are arranged in the fingers to adjust the gaps therebetween and grip the grinding elements between the respective pairs of fingers. Adjustable bolts 96a and 96b arranged in brackets 98a and 98b welded to the respective working arms 12a and 12b are adapted to position the grinding elements 10a and 10b transversely the inner working ends of the corresponding working arms 12a and 12b.

An unground workpiece 16 to be ground to a desired shape is mounted at the front of the machine between the grinding elements 10a and 10b. If the workpiece is in the form of a rough or unground stop cock, its cross arm 17 is supported in a clamp 100 mounted at the outer end of a rotatable shaft 102 driven by an electric motor 104. The inner end of the rough stop cock is supported by means of a centering member 106 slidably arranged upon the outer end of a horizontal shaft 108 locked by means of a setscrew 112 in an upright support member 110 mounted upon the base 18. The centering member 106 is fastened to the outer side of the flexible wall 22 and is normally urged forward by means of a coil spring 28.

The arrangement of working arms 12a and 12b, base plates 26a, 26b, 28a and 28b and guides 54a, 54b and 64a and 64b is symmetrical about the grinding axis X—X. However, minor deviations in the lengths of the projecting portions of the grinding elements may be accommodated by manipulation of the knobs 46a and 46b.

In practice, in the course of grinding small amounts, a grinding fluid (such as a water slurry of Carborundum) is applied from time to time to the surface to be ground. If desired, the surface may be sprayed with such fluid from a nozzle 110 and this fluid may drip into a pan 112 located

beneath the workpiece. In this arrangement the danger of lubricant reaching the working parts is minimized by the employment of the flexible wall 22.

When it is desired to grind a stop cock, the rough piece 16 is inserted between the two grinding elements 10a and 10b, the stop cock being abutted against the centering element 106 and being locked in place by the clamp 100. Generally speaking, the workpiece is pressed against the centering element 106 compressing the spring 28 to some extent. In placing the stop cock in grinding position the working arms of 14 are spread apart manually to the extent desired as indicated in Fig. 6.

The inner ends of the grinding elements 10a and 10b may be flat or curved, being curved especially after the grinding elements have been used a number of times. The grinding elements may be adjusted in position to engage the outer surface of the workpiece. In any event the length of the grinding elements project inwardly from the working arms 12a and 12b a distance sufficient to lift the working arms off the front vertical rollers 66a and 66b.

Thereafter, the motors 104 and 108 are energized causing the working arms 12a and 12b to be reciprocated back and forth as the workpiece 16 is rotated. During this action, the tension of the resilient member 14 presses the working arms against the rear vertical rollers 56a and 56b and also presses the grinding elements 10a and 10b against the outer surface of the workpiece 16 grinding it down as the operation continues.

The range of movement of the grinding elements is preferably regulated to assure grinding the rough stop cock throughout the entire length of the body portion to be ground into shape as illustrated in Figs. 7 and 8. Furthermore, the speed of movement of the working arms 12a and 12b is so selected relative to the width of the grinding elements, that the entire surface of the workpiece is subjected to contact with the grinding elements in each forward and rearward excursion of the working arms.

The tension of the resilient element 14 and hence the pressure of the grinding elements 10a and 10b upon the work piece remain substantially uniform until such time as the front ends of the working arms 12a and 12b engage the front vertical rollers 66a and 66b. At this point in the operation, the pressure of the grinding elements 10a and 10b upon the work piece 16, is relieved being taken up by the front vertical rollers 66a and 66b. Thus the front vertical rollers 66a and 66b together with the rear vertical rollers 56a and 56b establish ultimate grinding positions or lines of motion for the working arms and the grinding elements thereby causing the stop cock to be ground to a predetermined external conical configuration.

It will be understood from the foregoing that the final taper of the stop cock so formed is determined by the inclination of the working arms 12a and 12b to the grinding axis X—X as determined by the setting of the knobs 46a and 46b and that the size or diameter of the stop cock is determined by the spacing of the working arms 12a and 12b and the grinding axis X—X as determined by the setting of the wheel 38.

If a tapered joint is to be formed instead of a stop cock, it is convenient to employ a centering element 117 of the type illustrated in Fig. 10. This centering element is provided with a central outwardly projecting pointed spindle 118 which

is adapted to enter the mouth of the joint to be ground in order to enable it to be centered on the grinding axis X—X. With this particular arrangement other suitable clamping means is employed to support the tubular work piece 11 as it is rotated during the grinding operation.

From the foregoing it will be apparent that I have provided a grinding machine which facilitates the rapid manufacture of ground stop cocks and tapered joints and other ground articles at relatively high speed and low unit cost. Another advantage of my invention lies in the fact that tapered articles may be readily ground accurately to any predetermined size and shape.

While I have described my invention hereinabove with particular reference to the manufacture of stop cocks and joints having conical external surfaces, it will be readily understood by those skilled in the art that it may be readily adapted to the production of articles having surfaces of revolution of non-conical configuration. This may be accomplished by employing working arms that are curved instead of straight. Furthermore, though my invention has been described with particular reference to the forming of external surfaces of predetermined shape, it may, by suitable modification, be adapted to the grinding of internal surfaces. Various other changes which will suggest themselves to those skilled in the art may therefore be made in the material, form, details of construction and arrangement of the elements without departing from the principles of my invention. For example, suitable means are readily provided for adjusting the length of the stroke of the grinding elements and means, such as rollers, are readily provided for adjusting the position of the bed plate relative to the work-holding clamp. It is therefore to be understood that my invention is not limited to the specific embodiment thereof illustrated and described herein, but is capable of a wide variety of modifications, within the scope of the appended claims.

I claim:

1. In apparatus for grinding a work piece that is rotated about a grinding axis, a pair of grinding elements, means for urging said grinding elements against a surface of such workpiece, means for moving said grinding elements to and fro in a plane that includes said grinding axis while said workpiece is so rotated with said grinding elements urged thereagainst, and means including guide elements for limiting the movement of said grinding elements in a direction transverse to said surface whereby the pressure of said grinding elements on said surface is relieved when said surface has been ground to a predetermined shape.

2. In apparatus for grinding a work piece that is rotated about a grinding axis, a pair of grinding elements, means for urging a pair of grinding elements against opposite surfaces of such workpiece, means for moving said grinding elements in unison and to and fro in a plane that includes said grinding axis while said workpiece is so rotated with said grinding elements urged thereagainst, and means including guide elements for limiting the movement of said grinding elements in a direction transverse to said surface whereby the pressure of said grinding elements on said surface is relieved when said surface has been ground to a predetermined shape.

3. In apparatus for grinding a work piece that is rotated about a grinding axis, a housing having an apertured wall, a pair of bars extending

through said apertured wall, means for supporting a corresponding pair of grinding elements at the outer ends of said bars, a pair of guide means within said housing for establishing an ultimate grinding position for the respective grinding elements, each of said guide means comprising two spaced limit elements for supporting the corresponding bar when fully engaged thereby in an ultimate grinding position inclined toward a grinding axis, means for urging the respective bars toward the corresponding guide means, whereby said grinding elements engage the surface of said workpiece, and mechanism including interengaged mechanical elements mounted within said housing for longitudinally reciprocating said bars while urged toward said limit elements.

4. In apparatus for grinding a workpiece that is rotated about a grinding axis, a pair of grinding elements, means for urging said grinding elements inwardly against the outer surface of said workpiece on opposite sides thereof, means for moving said grinding elements to and fro in a plane that includes said grinding axis while said workpiece is rotated with said grinding elements urged against opposite sides thereof, and means including stops for limiting the inward movement of said grinding elements in a direction transverse to said surface whereby the pressure of said grinding elements on said surface is relieved when said surface has been ground to a predetermined shape.

5. In apparatus for grinding a workpiece that is rotated about a grinding axis, a pair of grinding elements, means for urging said grinding elements inwardly against the outer surface of said workpiece on opposite sides thereof, means for moving said grinding elements to and fro in a plane that includes said grinding axis while said workpiece is rotated with said grinding elements urged against opposite sides thereof, means including stops for limiting the movement of said grinding elements in a direction transverse to said surface whereby the pressure of said grinding elements on said surface is relieved when said surface has been ground to a predetermined shape, and means for adjusting the positions of said stops relative to said grinding axis whereby the size and shape of the finished article may be predetermined.

6. In apparatus for grinding a workpiece means including a pair of bars for supporting a corresponding pair of grinding elements respectively, a pair of guide means engageable with the respective bars for establishing an ultimate grinding position for the respective grinding elements supported thereby, each of said guide means comprising two spaced support elements for supporting each of the corresponding bars when fully engaged thereby in an ultimate grinding position inclined toward a grinding axis, means for urging the respective bars toward the corresponding guide means, means for supporting a workpiece in such a position as to be engaged by said grinding elements and to simultaneously hold said bars out of full engagement with said guide means, means for rotating the workpiece about the grinding axis while so supported, and means for longitudinally reciprocating said bars while said workpiece is rotated in engagement with said grinding elements, whereby said workpiece is ground to form a tapered surface of revolution thereon.

7. In apparatus for grinding a workpiece that is rotated about a grinding axis, a base, a pair of

rear guide means each including upper and lower rollers and an inner vertical roller mounted on said base on opposite sides of the grinding axis, a pair of front guide means each including upper and lower rollers and a vertical roller mounted on said base on opposite sides of the grinding axis, a pair of bars each mounted between upper and lower rollers of corresponding front and rear guide means on opposite sides of the grinding axis, means for mounting a pair of grinding elements at the front ends of the respective bars, means for laterally urging the respective bars toward vertical rollers on the corresponding guide means, and means for longitudinally reciprocating said bars while urged toward said vertical rollers.

8. In apparatus for grinding a workpiece that is rotated about a grinding axis, a base, a pair of rear guide means each including upper and lower rollers and an inner vertical roller mounted on said base on opposite sides of the grinding axis, a pair of front guide means each including upper and lower rollers and an inner vertical roller mounted on said base on opposite sides of the grinding axis, a pair of bars each mounted between upper and lower rollers of corresponding front and rear guide means on opposite sides of the grinding axis, mounting means for projecting a pair of grinding elements inwardly at the front ends of the respective bars, means for laterally urging the respective bars inwardly toward vertical rollers on the corresponding guide means, and means for longitudinally reciprocating said bars while urged toward said vertical rollers.

9. In apparatus for grinding a workpiece, a pair of bars, means for supporting a corresponding pair of inwardly projecting grinding elements on the respective bars, a pair of guide means for establishing an ultimate grinding position for the respective grinding elements, each of said guide means comprising two spaced support elements for supporting each of the corresponding bars when fully engaged thereby in an ultimate grinding position inclined toward a grinding axis, means for urging the respective bars inwardly toward the corresponding guide means, means for rotating the workpiece about the grinding axis while so supported, means for supporting a workpiece between said grinding elements with said bars out of full engagement with said guide means, and means for longitudinally reciprocating said bars while said workpiece is rotated in engagement with said grinding elements whereby said workpiece is ground to form a tapered surface of revolution.

10. In apparatus for grinding a workpiece that is rotated about a grinding axis, a bed plate, a pair of main base plates laterally movable on said bed plate transverse to the grinding axis, a pair of auxiliary base plates laterally movable on the respective main base plates transverse to the grinding axis, a pair of rear guide means mounted on opposite sides of the grinding axis, each rear guide means including a rear stop mounted on the respective main base plates, a pair of front guide means mounted on opposite sides of said axis, each front guide means including a front stop mounted on the respective auxiliary base plates, a pair of bars each operatively mounted between corresponding front and rear guide means on opposite sides of the grinding axis, means for laterally adjusting the position of each auxiliary base plate relative to the corresponding main base plate, whereby the inclination of each bar relative to the grinding axis

may be adjusted, means for mounting a pair of grinding elements at the front ends of the respective bars, means for laterally urging the respective bars toward stops on the corresponding guide means, and means for longitudinally reciprocating said bars while urged toward said stops.

11. Apparatus for grinding a workpiece that is rotated about a grinding axis, a bed plate, a pair of main base plates laterally movable on said bed plate transverse to the grinding axis, a pair of auxiliary base plates laterally movable on the respective main base plates transverse to the grinding axis, a pair of rear guide means mounted on the respective main base plates on opposite sides of the grinding axis each of said rear guide means including upper and lower rollers and an inner rear vertical roller, a pair of front guide means mounted on the respective auxiliary base plates on opposite sides of the grinding axis, each of said rear guide means including upper and lower rollers and an inner front vertical roller, a pair of bars each mounted between upper and lower rollers of corresponding front and rear guide means on opposite sides of a

19
